UNITED STATES PATENT OFFICE.

ARCH B. COATES, OF ELLSWORTH, KANSAS, ASSIGNOR, BY DIRECT AND MESNE ASSIGNMENTS, TO ECONOMY FORCED DRAFT SLACK BURNER COMPANY, OF ELLSWORTH, KANSAS.

GRATE.

Specification of Letters Patent.

Patented Dec. 8, 1914.

1,119,808.

Application filed June 17, 1913. Serial No. 774,226.

To all whom it may concern:

Be it known that I, ARCH B. COATES, citizen of the United States, residing at Ellsworth, in the county of Ellsworth and State of Kansas, have invented certain new and useful Improvements in Grates, of which the following is a specification.

My present invention relates to an improved grate construction for steam boilers, and more particularly to an improvement over the grate construction set forth in my co-pending application filed April 15, 1913 and bearing Serial Number 761,378, the primary object of the present invention being the provision of a grate possessing all the advantages incident to the grate construction set forth in the above named application and at the same time one which is more economical in construction and more readily applied to furnaces now in use.

A further object of my present invention is to provide a grate having hollow grate bars so formed that the grate may be used either in connection with a forced draft or in connection with a natural draft, as desired.

A further object of my invention is to so construct the grate that fine fuels may be burned thereon without waste, as the complete grate forms in effect a continuous floor or fuel bed, only such narrow spaces as are requisite for the necessary draft being formed in the grate bars, and because of this construction practically no ashes will pass through the openings in the grate bars and such ashes as do fall through will fall to the ash pit in the furnace, in no way interfering with the draft.

In this connection, when the above grate is provided with a forced draft, the draft is so arranged and applied that it may be employed in blowing out and thereby removing the ashes from the ash pit.

With these and other objects in view, my invention will be more fully described, illustrated in the accompanying drawings and then specifically pointed out in the claim which is attached to and forms a part of this application.

In the drawings: Figure 1 is a sectional view of a conventional form of boiler and boiler furnace showing the application of a grate constructed in accordance with my present invention; Fig. 2 is a fragmentary top plan view of the grate; Fig. 3 is a longi-

tudinal section through one of the grate bars shown in Fig. 2; Fig. 4 is a transverse section of Fig. 3 looking toward the rear; Fig. 5 is a perspective view of one of the grate bars employed in the grate shown in Figs. 1 to 4, inclusive, of the drawings.

To insure a clear understanding of the construction and operation of my improved grate, I have illustrated the same in connection with a boiler and a boiler furnace of conventional design in which 10 indicates the front wall of the furnace, 11 the bridge wall, 12 the floor or base, 13 the ash pit and 14 the fire box. The front wall is provided with the usual door openings and doors permitting communication with the ash pit and fire box, the door to the fire box being indicated by the numeral 15 and being hinged to swing into closed position against a rectangular door frame 16 having a dead plate 17. 70 The grate, which is indicated as a whole by the numeral 18, is supported on a level with the dead plate by two or more transverse supporting bars 19, bearing at its rear end against the bridge wall and at its forward end against the dead plate of the door frame. 75

Referring more specifically to Figs. 2 to 5 of the drawings, it will be noted that the grate is made up of separate and unconnected grate bars, each indicated as a whole by the numeral 20. Each of these grate bars consists of spaced apart vertical side walls 21, front and rear walls 22 and 23 connecting the end portions of the side walls, and cross braces 24 arranged at suitable intervals and connecting the side walls, all of said parts being cast or otherwise integrally formed. It will be noted that at the outer end of the grate bar the side walls are somewhat higher than throughout the remainder of their length, the front wall being higher than the rear wall and the side walls having their upper forward edges inclined, as clearly shown in Figs. 3 and 5 of the drawings.

The main body of the grate bar, as above described, is open at its bottom and is normally closed at its top by draft plates 25 and 26 the former of which extends from the rear or inner end of the grate bar to that point where the side walls are extended upwardly and the latter of which is seated upon said latter portions of the side walls and consequently at an inclination to the plate 25. This manner of constructing the 105 110

grate bars causes the grate to be slightly higher adjacent the door than at other points and therefore insures the proper positioning of the fuel upon the grate. These draft 5 plates are secured to the body of the grate bar proper by bolts 26' passed through the draft plates and braces 24 and secured by nuts 27, the heads of the bolts being countersunk in the upper faces of the draft plates. 10 Each of the draft plates 25 and 26 is provided with a plurality of draft openings in the form of narrow, elongated, unconnected slots 28. These slots may be arranged in any suitable position with respect to each 15 other, although the herring bone arrangement illustrated in the drawings is preferred. The body proper of the grate bar is provided at its lower edge with a laterally directed marginal flange 29 which extends completely around the grate bar and the purpose of which will be hereinafter explained. In constructing the grate the grate bars are mounted one beside the other with the spacer flanges 29 of one bearing against 20 the spacer flanges of the adjacent bars and against the dead plate and bridge wall of the furnace, which spaces the grate bars a slight distance from each other, and from said walls to allow for expansion of the 25 metal of which they are formed, when heated. The spaces thus formed between the upper portions of the grate bars and between the upper portions of the dead plate and bridge wall are filled with a packing 30 of asbestos wool or other suitable heat-resisting material which will prevent the accumulation of ashes between the bars and provide a continuous uninterrupted floor or fuel bed, while at the same time it will permit 35 the bars to expand.

It will be apparent that with a grate of the above described character a natural draft, through the door or door opening of the ash pit, will in many instances be sufficient. If, however, a forced draft is desired, air may be driven into the ash pit beneath 45 the grate through a pipe or other suitable conduit 31, the air being supplied to the pipe from any suitable source as a blower 50 conventionally shown at 32.

It should be noted that no ashes or other waste can pass through the grate except through the draft openings 28 thereof and the draft passing through these openings to 55 the fire will usually be sufficient to keep them clear of ashes. Any ashes or waste, however, which does pass through these

openings will be accumulated in the ash pit of the furnace and may be removed from it by opening the door to the ash pit and 60 blowing the same out by means of a forced draft from the blower 32.

The grate bars may be made in various sizes and proportions to suit the type of fire box with which they are to be used and 65 may of course be supported in any suitable manner in the fire box. The type of grate construction above described is extremely effective in operation, greatly increasing the heating capacity of the furnace, due to a 70 more complete combustion of the fuel used therein. Each grate bar being entirely separate and independent of the others is perfectly free to expand in any direction, and in case of injury may be readily removed 75 for repairs or replaced by another without disturbing the remainder of the grate.

It will of course be understood that various changes, within the scope of the appended claim, may be made at any time in 80 the construction of the grate bars or in the manner of assembling or forming the complete grate without in the slightest degree departing from the spirit of my invention.

By forming the draft plates separable 85 from the bodies of the grate bars it will be apparent that in case any draft plate becomes broken, burnt out or otherwise injured, it may be removed and replaced by another without the necessity of removing 90 the entire grate bar. The ash pit is air tight and the air is compressed in the ash pit and forced through the slots of the grate.

Having described my invention, what I claim is:

In a grate construction, a hollow grate bar including spaced side and end walls having their lower edges in the same plane, and transverse braces connecting the side walls, all of said parts being integrally 100 formed, the walls at their lower edges being provided with outwardly directed spacer flanges, plates resting on the upper edges of the walls and provided with a plurality of openings for the passage of air through 105 the grate bars, and fastening devices inserted through said plates into and through the braces.

In testimony whereof I affix my signature in presence of two witnesses.

ARCH B. COATES. [L.S.]
